UNITED STATES PATENT OFFICE.

MAURICE C. TURNER, OF NEW YORK, N. Y.

TELEPHONE-BOOTH.

1,294,202.

Specification of Letters Patent. Patented Feb. 11, 1919.

Application filed November 17, 1910. Serial No. 592,944.

To all whom it may concern:

Be it known that I, MAURICE C. TURNER, of the city of New York, State of New York, have invented certain new and useful Improvements in Telephone-Booths; and I do hereby declare the following to be a full, clear, and exact description of the invention, such as will enable others skilled in the art to which it appertains to make and 10 use the same.

This invention relates to cabinets or booths, such as telephone booths, having special reference to the doors thereof.

In Letters Patent No. 822,493, issued to the 15 New York Telephone Company June 5th, 1906, on my application, I have shown a telephone booth equipped with a one-piece door supported by radial arms pivoted at the top and bottom of the booth and movable 20 in curved guides so that the door in opening moves into the booth.

This door, known commercially as the receding type, while thoroughly efficient and successful because it effects economy of 25 space, allows of ventilation, and renders each booth self contained, has, however, some objectional characteristics which my present invention tends to eliminate. The operation of the patented receding door is 30 frequently noisy, thus disturbing the conversation of patrons in adjacent booths. This is partly owing to the roller traveling in its groove and partly to the fact that the sound of loud voices escapes through the slot in the 35 booth, and also to the fact that the door is often closed violently. The receding doors of the patented type occasion annoyance to patrons unfamiliar with them, and their mechanism sometimes becomes defective.

40 The preferred form of embodiment of my improved booth is illustrated in the accompanying drawings where Figure 1 is a front elevation with the door closed; Fig. 2 a transverse section on line 2—2, Fig. 5; Figs. 45 3 and 4 horizontal sections on lines 3—3 and 4—4 respectively, Fig. 1; Fig. 5 a top plan view of the booth with the top or cover removed; Fig. 6 a fragmentary perspective, and Fig. 7 a slight modification.

50 Referring to the drawings 1 designates one of the cabinets or telephone booths, a series of which latter may be arranged under the control of a switchboard attendant, each booth constituting a complete inclosure and 55 equipped with a telephone instrument and a

door constructed in accordance with my invention.

The door 2 comprises two leaves or sections hinged together at their vertical meeting edges to constitute an inward folding 60 closure. The stile of the leaf 3 is hinged to the door frame of the booth as at 5 and mounted so as to just swing clear of the floor. The leaf 4 is hinged to leaf 3 as at 6.

In order to provide an efficient joint between the two leaves and at the same time make provisions against patrons having their fingers injured by carelessly operating the doors, I form the meeting edge of leaf 3 with a bead 7 and the edge of leaf 4 70 with a corresponding groove 8, the bead in the embodiment illustrated being interrupted at the points of location of the hinges 6. By placing these hinges beyond the point at which a person would be apt to grasp the door the danger of injury to the hand is overcome. At its meeting edge each of the leaves is shown tapered or beveled from its inner face to the joint between the leaves, as 75 at 7^a. This avoids square or angular corners and prevents injury to the fingers. I have shown each of the leaves formed with a lip or flange 9 adapted to close the spaces between the edges of the leaves and the frame at 80 as at 7^a. This avoids square or angular corners and prevents injury to the fingers. I have shown each of the leaves formed with a lip or flange 9 adapted to close the spaces between the edges of the leaves and the frame 85 when the door is closed. An operating handle 10 is shown on the inner face of leaf 4 at its meeting edge. As clearly illustrated, the bead 7 projects outward from the leaf to which it is secured, that is, at an angle to the plane of the outer face of the leaf. Consequently when the door is fully closed and the leaves are in alinement the bead projects outward from the plane of the outer face of the door (see Fig. 3). This provides a 90 surface around which the complementary groove of the other leaf may turn in assuming the position of Fig. 5. This result could not be attained if the bead were within the thickness of its leaf.

In the top of the booth is shown a track or guide 12, the leaf 4 having a pin or stud 13 at its top designed to travel in the track. This track through the greater part of its length is shown curved to conform to the swing of the leaves and terminates as at 16 100 in a relatively straight portion substantially parallel with the plane of the door when closed.

I have shown the two leaves of different widths, the purpose of this construction be- 105

ing merely to effect economy of space. The opening movement of the door as shown in dotted lines, Fig. 5, as well as the fully open position shown in full lines, insures ample space within the booth, leaf 4 projecting from the booth approximately three inches when the door is fully open. The leaf 4 is shown provided with a single glass panel 14 but obviously both of the leaves 10 may be so equipped. 15 is a buffer or pillow block on the wall of the booth to deaden the sound of the door reaching the limit of its opening movement.

In the use of heavy doors it may be desirable to provide supporting means in addition to that afforded by the hinges. For this purpose I have shown in Fig. 7 the lower partition 17 of the double ceiling formed with a groove 18 in its upper face 20 through which a roller 19 is movable, the roller carrying a bracket 20 secured to leaf 4 of the door. In the drawings I have shown the door hinged at the left hand side of the cabinet but in actual practice when 25 applied to telephone booths I find it more advantageous to hinge the door at the right hand side as viewed from the front, since thereby the user has his left hand free for manipulating the telephone receiver while 30 his right hand is free to operate the door. It will be understood that the door may be hinged at either side without departing from the spirit of my invention as defined by the claims.

35 The operation is simple and easily accomplished. When the booth is not in use the door is open as in Figs. 2 and 5. The patron on entering the booth grasps the handle 10. In nearly every instance this 40 action with one hand is accompanied by a removal of the telephone receiver from its hook with the other hand and simultaneously the patron begins speaking. Consequently it is necessary for practical success 45 that the door offer no resistance to closing and that the patron's conversation be not interrupted by noise and also that the action required to operate the door will not necessitate the user moving from his position at 50 the transmitter. These results are fully attained by the described construction. It has been demonstrated that with the handle 10 at the fulcrum point the slightest pressure upon the handle will communicate sufficient movement to the leaves to indicate to 55 the patron the direction in which the leaves move. This point of location of the handle, however, owing to its proximity to the joint might cause the user to pinch his fingers 60 between the leaves were it not for the tapered portions 7^a or the bead and groove connection. This makes it impossible to pinch the fingers, so that the operator may with perfect safety operate the door without turning his head from the instrument. 65

In this connection it will be noted that the door necessarily moves quietly, being supported only by the hinges. If it be violently closed the force will be in a large measure taken up by the air compressed within the 70 booth. This, with the line of direction of leaf 4 as it reaches the frame, reduces its impact and no objectionable noise results. To open the door the patron within the booth simply pulls the handle 10, this force 75 being communicated by the track to the hinge connection between the leaves. A person of average size, to emerge from the booth, moves the door to the full line position of Fig. 5 thus leaving the outer free 80 edge of leaf 4 projecting but slightly beyond the booth.

The principal features of advantage to the users of a booth embodying my invention are safety and ease of operation and 85 the absence of noise, the doors themselves moving quietly and the booths being virtually sound proof owing to the absence of slots and the complete seal provided by the door in its closed position. Among the advantages from the manufacturer's standpoint are that the folding door may be made at less cost than the receding door and may be readily assembled when the booths are shipped, collapsed or "knocked down." 90 The door when fully open does not extend so far into the booth as to necessitate slotting the seat within the booth. The doors of all types of booths now in use may be replaced by the folding door and the latter, 100 owing to the few mechanical parts, insures a minimum cost of maintenance.

I claim as my invention:—

1. A cabinet adapted to be entered by the user, a door therefor adapted to be operated 105 by the user within the cabinet, said door comprising leaves hingedly connected at the outer faces thereof to fold within the cabinet, and having their inner contiguous edges tapered or beveled to provide a space 110 between said edges and thus present no pinching parts as the door is opened or closed.

2. A cabinet adapted to be entered by the user, a door therefor adapted to be operated 115 by the user within the cabinet, said door comprising leaves hingedly connected to fold within the cabinet and having a bead and groove connection between said leaves, the connection being so constructed as to 120 present no pinching parts as the door is closed or opened.

3. A cabinet adapted to be entered by the user, a door therefor adapted to be closed or opened by the user within the cabinet, 125 said door comprising leaves connected together to fold within the cabinet, said leaves having a bead and groove connection, said bead projecting outward beyond the plane of the outer face of the door. 130

when the leaves are closed, the inner faces of said leaves having their contiguous edges beveled.

4. A cabinet adapted to be entered by the user, a door therefor adapted to be closed or opened by the user within the cabinet, said door comprising leaves connected together to fold within the cabinet, said leaves having a bead and groove connection, said bead being secured to one of the leaves and projecting outward at an angle to the plane of the outer face of the leaf, the other leaf having a groove to receive said bead, and the inner faces of said leaves having their contiguous edges beveled.
5. A cabinet adapted to be entered by the user, a door therefor adapted to be operated by the user within the cabinet, said door comprising leaves connected together

so as to fold within the cabinet, one of said leaves having a bead at its meeting edge projecting outwardly beyond the plane of said leaf and terminating in a bevel on the inner side of said leaf, and the other of said leaves having a groove to receive said bead, said last mentioned leaf having a complementary bevel on its inner face, said bead and the beveled portions of said leaves constituting an anti-pinching finger surface between said leaves.

In testimony whereof, I have signed this specification in the presence of two subscribing witnesses.

M. C. TURNER.
